UNITED STATES PATENT OFFICE.

VIRGINIUS Z. CARACRISTI, OF BRONXVILLE, NEW YORK, ASSIGNOR TO LOCOMOTIVE PULVERIZED FUEL COMPANY, OF NEW YORK, N. Y., A CORPORATION OF DELAWARE.

MEANS FOR THE BURNING OF PULVERIZED FUEL AND GAS.

Application filed May 23, 1919. Serial No. 299,327.

To all whom it may concern:

Be it known that I, VIRGINIUS Z. CARACRISTI, a citizen of the United States, and a resident of Bronxville, in the county of 5 Westchester and State of New York, have invented certain new and useful Improvements in Means for the Burning of Pulverized Fuel and Gas, of which the following is a specification.

10 The present invention relates to improvements in means for the burning of pulverized fuel and gas and has particularly for an object the efficient burning of low grade combustible gas in combination with the burning of pulverized coal, by utilizing the pulverized coal as a regenerative or auxiliary heating agent to assist in the complete combustion of the gas. It will be understood, however, that other auxiliary fuel than pulverized coal may be utilized in the burning 15 of low grade gas to produce a regenerative or auxiliary heating effect upon the gas according to my invention.

20 Low grade gas is burned with difficulty under ordinary conditions. Certain methods heretofore in use consisted in passing a current of low grade gas over a body of coal fire which supplied heat for effecting complete combustion of the gas, but from which 25 no other direct benefit was obtained, i. e., the net result upon the heat absorbing parts of the furnace was only the heating effect obtained from the burning of the gas. Heat for the same purpose has also been provided by means of large regenerative reverberatory brick surfaces in the furnace.

30 As indicated above, I aim to overcome all such difficulties and effect complete combustion of low grade gas to the best advantage by heating the gas with auxiliary fuel, preferably in such a way that both the gas and the auxiliary fuel contribute directly to the useful heating effect. For this purpose, I may provide a flame of pulverized 35 fuel and air in combination with a gas flame, and may so arrange the combustion apparatus or furnace that the gas is forced into or through the current of pulverized fuel in its progress to the stack. As the 40 gas mixes into the current of pulverized fuel under these conditions, the incandescent particles of coal will become surrounded by an intimate (even molecular) mixture of the combustibles of the gas with oxygen,—

sufficient air to support combustion being 55 fed in with the gas. Thus innumerable combustion zones will be created in the furnace and complete combustion of both coal and gas obtained, with maximum heating effect from both,—the one acting contemporaneously as an auxiliary heating agent for bringing about the complete combustion of the other.

In the accompanying drawings:

Figure 1 is a vertical sectional view of a 60 furnace of the boiler type embodying one form of my invention;

Figure 2 is a front elevation of the type 65 of burner employed in the embodiment of my invention shown in Figure 1;

Figure 3 is a horizontal sectional view taken along the line 3—3 of Figure 2;

Figure 4 is a vertical sectional view taken along the line 4—4 of Figure 2; and

Figure 5 is a diagrammatic view showing 70 one of the minute combustion zones comprising an incandescent particle of coal and molecules of combustibles of the gas and oxygen surrounding the same.

Similar reference characters indicate corresponding parts throughout the several figures of the drawings.

Referring to Figure 1 of the drawings, the furnace shown therein comprises a combustion chamber 10 with a forwardly projecting mixing space 11 in the top wall 12 of which there is mounted an upright combination pulverized fuel and gas burner, the gas burner portion being adjacent the upright or perpendicular front wall 13 of the 85 furnace. The front wall 13 is provided with auxiliary air feed openings 13^a having dampers 13^b, and with a lower cleanout opening 13^c.

In Figures 2, 3 and 4, I have illustrated 90 the combination burner as comprising a lower casing 14 of rectangular cross section into which extend the ends of the pulverized fuel feed pipes 15 which are surrounded by air channels 16 open to the atmosphere at 17 and adapted to be controlled by dampers 18. Separate streams of fuel are induced 95 through the several pipes 15 by steam or air jet nozzles 19 and these streams of fuel with the surrounding air from the channels 100 16 are separated by streams of air entering the furnace through air spaces 20 and 21, which are open to the atmosphere at 22 and

are controlled by dampers 23. By this means of feeding and mixing fuel with air, there is obtained a more perfect mixture of the fuel and the combustion air, which permits rapid combustion to take place.

In front of the fuel burners there are a pair of gas burners with their outward end portions 24 and 25 directly in front of the pulverized fuel burner outlets. These gas burners extend in oppositely inclined directions, as at 26 and 27, to the sides of the fuel burners, where they are connected to the vertically disposed air inlets 28 and 29 and the horizontally disposed gas inlets 30 and 31. Within the gas burners are a plurality of spaced hollow walls or casings 32 between which the gas flows from the inlets 30 and 31, and through which air flows from the air inlets 28 and 29, with which the spaces within the walls are in communication. The gas becomes mixed with the air as it emerges from the outlets of the burners.

In Fig. 1 the heavy arrows indicate the flow of pulverized fuel and air, while the light arrows indicate the flow of combustible gas. The combustion chamber 10, it will be seen, has exit for flame and products of combustion at its rear, over a barrier or bridge wall 33 at the rear of the chamber. The combustion stream of pulverized fuel directed downward into the front portion 11 of the combustion chamber 10 from the corresponding burners descends and curves rearward therein, finally doubling on itself and escaping at the exit over the wall 33. The stream of low-grade combustible gas (with air) directed downward into the space 11 from the corresponding burners in front of the pulverized fuel stream likewise descends and curves rearward in the combustion chamber, in front or outside of the pulverized fuel stream,—in reference to the combustion chamber and the exit over the wall 33. In other words, the streams of pulverized fuel and gas are introduced into superposition as and after they enter the furnace, the current of pulverized fuel and air being uppermost in the furnace in its progress to the stack.

The rear wall 33 of the furnace is of such height that the lower edge or limit of the stream or current of pulverized fuel and air passes just over the top of said wall; and thus there is formed below and in front of said stream a gas confining space bounded by the stream, the rear wall 33, the floor of the furnace, and the front furnace wall 13. In this space, a primary heating of the gas is produced by radiation from the walls of the furnace (as indicated by the small arrows 34),—as well as by radiation and conduction from the juxtaposed burning fuel stream to some extent.

By the time the flaming pulverized fuel stream has about reached the low point of its

curving course through the chamber 10, incandescence of partly unburned particles therein has developed. At this point, the tendency of the subjacent flaming gas to rise and mingle in the pulverized fuel stream (indicated by a few upward-curving light arrows in Fig. 1) is strongly supplemented by the deflecting action of the wall 33 and of the upward sloping rear portion of the furnace floor. The draft through the furnace, therefore, causes the gas flame to be forced substantially transversely into and through the superjacent current of pulverized fuel approaching and passing over the barrier 33,—as clearly indicated by the light arrows in Fig. 1.

As the gas flame is drawn into the flame of pulverized fuel and air, each of the innumerable incandescent particles of coal 35 (Fig. 5) in the latter becomes surrounded with a zone of low grade gas and air. In this gas zone, the combustible molecules 36 of the gas and the oxygen molecules 37 of the air form, again innumerable minute combustion areas about the incandescent carbon particle, which are heated and kept in combustion by its combustion and incandescence. Through this auxiliary heating of the low grade gas with its admixed supply of oxygen, complete combustion of the gas is secured, as well as of the coal. Thus the gas and coal flames are fully and complementarily developed and maintained, with maximum efficiency and heating effect from both fuels, and without loss in the final application of heat to the absorbing parts of the furnace or boiler.

It will be understood that the burner may be a single unit comprising pulverized fuel feeding means and gas feeding means, or the pulverized fuel feeding means and the gas feeding means may be separated, the arrangement desirable for the purposes of my invention being one such that gas is fed in combination with an auxiliary fuel in separate superimposed streams, and the gas forced into the current of the auxiliary fuel in such manner that the incandescent particles of the auxiliary fuel furnish auxiliary heat for the complete combustion of the gas.

I have illustrated and described preferred and satisfactory embodiments of my invention but it is obvious that changes may be made therein within the spirit and scope thereof as defined in the appended claims.

I claim:

1. Apparatus for burning fuels in a furnace provided with means creating a draft comprising a combustion chamber having a waste outlet in an upper part, means for admitting pulverized coal in an upper part of the chamber to one side of the said outlet and adjacent a wall of the chamber and in a downward direction, and means for

separately admitting a combustible gas into the combustion chamber in the upper part thereof in a downward direction into the space between the descending coal and such 5 wall.

2. Apparatus for burning fuels in a furnace provided with means creating a draft comprising a combustion chamber having a waste outlet in an upper part, means for admitting pulverized coal in an upper part of 10 the chamber to one side of the said outlet and adjacent a wall of the chamber and in

a downward direction, and means for separately admitting a combustible gas into the combustion chamber in the upper part 15 thereof in a downward direction into the space between the descending coal and such wall, together with means for admitting air through such wall.

In testimony that he claims the foregoing 20 as his invention, he has signed his name hereunder.

VIRGINIUS Z. CARACRISTI.
